(57) **CLAIM**

The ornamental design for a cover for pot lid knob, as shown and described.

DESCRIPTION

FIG. 1 is a front elevational view of a cover for pot lid knob showing my new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a top front perspective view thereof.

FIG. 8 is a bottom rear perspective view thereof.

FIG. 9 is a cross-sectional view thereof, taken along line 9-9 of FIG. 1; and,

FIG. 10 is a top front perspective view thereof, in use condition.

The broken lines illustrate environmental structure and form no part of the claimed design.
